PREPARATION OF ALKYL AMINOSULFIDES

John E. Mahan, Bartlesville, Okla., assignor to
Phillips Petroleum Company, a corporation of
Delaware

**No Drawing. Application December 3, 1948,
Serial No. 63,433**

10 Claims. (Cl. 260—563)

1

This invention relates to new and novel compositions and to their preparation. In another aspect this invention relates to alkyl aminoalkyl sulfides and alkyl aminocycloalkyl sulfides. Another aspect of this invention relates to a process for the production of alkyl aminocycloalkyl sulfides.

An object of this invention is to provide alkyl aminocycloalkyl sulfides as new compositions.

alkyl aminoalkyl sulfides as new compositions. Another object is to provide a process for the production of alkyl aminoalkyl sulfides and alkyl aminocycloalkyl sulfides.

Another object is to provide a process wherein an amino sulfuric acid is reacted with an aliphatic mercaptan to produce a corresponding sulfide.

Other objects will be apparent, to those skilled in the art, from the accompanying discussion and disclosure.

In accordance with my invention alkyl amino-cycloalkyl sulfides and alkyl aminoalkyl sulfides are prepared by the interaction of an aliphatic mercaptan with a molar equivalent of a selected amino sulfuric acid in the presence of an alkaline-reacting agent. The following equation is illustrative of my invention.

In each of the above compounds, R is selected from the group consisting of primary, secondary and tertiary alkyl radicals containing not more than 16 carbon atoms, R' is selected from the group consisting of alkylene, cyclopentylene, and cyclohexylene radicals containing not more than 10 carbon atoms, R'' is selected from the group consisting of hydrogen, alkyl, aryl and aralkyl radicals, R''' is selected from the group consisting of hydrogen alkyl, aryl and aralkyl radicals, and R'' and R''' may form a heterocyclic ring together with the nitrogen, the sum of the number of carbon atoms in R'' and R''' not exceeding 10. The alkyl amino sulfides produced in accordance with my invention may be converted to their quaternary salts which are important materials in the manufacture of detergents and surface active agents. In view of the thioether linkage present, these compounds may be converted by oxidation to amino sulfoxides and sulfones.

Among the aliphatic mercaptans that may be employed in the practice of my invention are, propylmercaptan, n-butylmercaptan, isobutyl-

2

mercaptan, tertiary butylmercaptan, n-pentylmercaptan, isoheptylmercaptan, iso-octylmercaptan, n-decylmercaptan, n-dodecylmercaptan, tert-dodecylmercaptan, n-hexadecylmercaptan, and the like.

Amino sulfuric acids that may be employed herein include various types depending on the specific composition being prepared. For example, in the production of alkyl primary amino-alkyl sulfides, a primary amino sulfuric acid such as 2-amino-1, 1-dimethyl-ethyl sulfuric acid may be employed; in the production of an alkyl secondary amino alkyl sulfide, an N-alkyl amino-alkyl sulfuric acid such as N-methyl-2-amino-ethyl sulfuric acid may be employed; and in the production of an alkyl tertiary aminoalkyl sulfide an N,N-di-alkyl aminoalkyl sulfuric acid such as N,N-dimethyl-2-amino ethyl sulfuric acid may be employed. In the production of alkyl 20 aminocycloalkyl sulfides such as an alkyl primary aminocycloalkyl sulfide, an amino sulfuric acid such as 4-aminocyclohexyl sulfuric acid or 3-aminocyclopentyl sulfuric acid may be employed; in the production of an alkyl secondary 25 aminocycloalkyl sulfide an amino sulfuric acid such as N-methyl 4-aminocyclohexyl sulfuric acid or N-ethyl 2-aminocyclopentyl sulfuric acid may be employed; and in the production of an alkyl tertiary aminocycloalkyl sulfide, an amino 30 sulfuric acid such as N,N-dimethyl 3-aminocyclopentyl sulfuric acid or N,N-dimethyl 4-aminocyclohexyl sulfuric acid may be employed. Among the amino alkyl sulfuric acids that may be used in the preparation of an alkyl amino sulfide wherein the R''s form a ring of which nitrogen is a part, are, morpholinyl sulfuric acids 35 such as morpholinyl methyl sulfuric acid.

morpholinyl 2-cyclopentyl sulfureic acid

and morpholinyl 4-cyclohexyl sulfuric acid

pyrrolidyl sulfuric acids such as pyrrolidyl methyl sulfuric acid,

pyrrolidyl 3-cyclopentyl sulfuric acid,

and pyrrolidyl 3-cyclohexyl sulfuric acid,

and piperidyl sulfuric acids such as piperidyl ethyl sulfuric acid,

piperidyl 4-cyclohexyl sulfuric acid,

and piperidyl 3-cyclopentyl sulfuric acid

The alkyl aminocycloalkyl sulfides as described herein above are new compositions.

Alkaline-reacting agents referred to herein preferably include the alkali metal oxides and hydroxides, and the alkaline salts of the alkali metals, such as sodium carbonate. Alternately, alkaline earth metal oxides and hydroxides, and mixtures of alkali metal and alkaline earth metal oxides or hydroxides may be employed as alkaline-reacting agents, in the practice of my invention. At least one mole, preferably two moles, of alkaline-reacting agent are employed per mole of total mercaptan and amino sulfuric acid reactants. Sometimes 3 moles or more, of alkaline-reacting agent per mole of total reactants may be advantageously employed. Although the general equation presented above shows sulfuric acid as one of the reaction products, it immediately reacts with the alkaline-reacting agent to form the corresponding salt.

In a preferred embodiment of my invention, a selected aliphatic mercaptan is co-mingled with a selected aqueous amino sulfuric acid, in a mole ratio of mercaptan to the acid usually within the limits of from 1:1 to 1:3, in the presence of an alkaline-reacting agent of the type already described, preferably aqueous sodium hydroxide, and the resulting reaction mixture is heated for a period of from about 2 to 48 hours with constant agitation. The reaction may be conveniently conducted under reflux. At the end of the reaction period, the reactants are cooled and the crude product is removed and purified.

In another embodiment of my invention the

aliphatic mercaptan reactant is comingled with the amino sulfuric acid reactant, in a mole ratio of mercaptan to the acid usually within the limits of 1:1 to 1:3, in the presence of an alkaline-reacting agent of the type already described; the resulting admixture is then heated for a period of from 10-15 hours at a temperature in the range 100-110° C. and thereafter for a period of from 20 to 30 hours at a temperature higher than 110° C. and not above 150° C.

I prefer usually to conduct the product-forming step at a temperature in the range of from 50 to 150° C. for a period usually of from 1 to 48 hours, although in some instances shorter or longer reaction times may be advantageously employed.

I may employ pressures varying from subatmospheric to superatmospheric, usually in the range of from atmospheric pressure to 250 p. s. i. g. After the desired reaction period, the reaction mixture is cooled, and may be admixed with excess 50 per cent alkali at a temperature below from 10 to 15° C., preferably ice temperature, to cause dissolution of any sulfide product and to dissolve any unreacted mercaptan and/or acid.

The product phase is an oil, and may be readily separated from the aqueous layer and dried in any suitable manner.

As already stated, the excess 50 per cent aqueous alkali hydroxide is employed as a means of

effecting separation of the oil product from the water solution. In this step of my process from 1 to 2 moles of alkali, in 50 per cent aqueous solution, per mole of sulfide product in the reaction mixture may be advantageously employed.

However, other suitable means of separating the sulfide product from the reaction mixture, such as solvent extraction, may be utilized. Ether may be advantageously employed as a solvent, and the extract may be distilled to yield a purified sulfide product. In some instances high molecular weight product may be formed which is non-soluble in water solution, in which case treatment with aqueous alkali reagent would be unnecessary. Other means than the use of aqueous alkali, known to those skilled in the art, for effecting such a separation of sulfide product from the reaction mixture may be used in the practice of this invention.

Although the use of an aqueous reaction medium is advantageous for carrying out the process of my invention, other solvents, particularly an alcohol, may be employed. In those cases where in the non-aqueous medium is employed, use of the metal mercaptide in place of the mercaptan may be advantageous.

Although the process of this invention is described with particular reference to batch-wise operation, it may be carried out in a continuous operation when desired. Such an embodiment of the process presents definite advantages in large scale operation and is within the scope of this invention.

My invention is illustrated by the following examples. The reactants, their proportions, and other specific ingredients are presented as being typical and should not be construed to limit the invention unduly.

Example 1

A run was made wherein tert-butyl mercaptan, 2-aminoethyl sulfuric acid, and 10 per cent aqueous sodium hydroxide were charged to a closed reactor in a respective 1:1:2 mole ratio. The temperature was then raised to 107° C. and the reaction mixture was maintained at that level for 6 hours with continuous agitation. The

reaction mixture, after cooling, was treated with excess 50 per cent aqueous sodium hydroxide at ice temperature to cause dissolution of any sulfide product and to dissolve any unreacted mercaptan. The product was purified by extraction with ether and distilled under vacuum. A yield of 51.9 mole per cent of 2-aminoethyl-tert-butyl sulfide was obtained. A redistilled portion of the 2-aminoethyl-tert-butyl sulfide product had a boiling point of 64.8-65.8°C. and a refractive index, n_D^{20} , of 1.4787. The determined molecular weight of the product was 138.3. The hydrochloride of this product had a melting point of 208-209°C.

Example 2.

A run was made wherein tert-octyl mercaptan prepared by reacting a mixture of octenes with hydrogen sulfide in the presence of an alumina-type catalyst, 2-aminoethyl sulfuric acid, and 10 per cent aqueous sodium hydroxide were charged to a closed reactor in a respective 1:1:2 mole ratio. The temperature was then raised to 104°C. and maintained between 104 and 110°C. for 15 hours with continuous agitation. The temperature was then raised to 149°C. and maintained at that level for an additional 23 hours with agitation. The sulfide product was purified as in Example 1. A redistilled portion of the 2-aminoethyl-tert-octyl sulfide product obtained had a boiling point of 114-115°C. and a refractive index, n_D^{20} , of 1.4888. The determined molecular weight of the product was 195.1. The hydrochloride of this product had a melting point of 182-186°C.

Example 3.

4-aminocyclohexyl-tert-butyl sulfide is prepared by following the procedure described in Example 1, except that 4-aminocyclohexyl sulfuric acid is used in place of 2-aminoethyl sulfuric acid. The yield, after purification by distillation under vacuum, is 38 mole per cent. The molecular weight of the product is 195.

Example 4.

2-aminoethyl-n-propyl sulfide is prepared by reacting 1 mole of n-propyl mercaptan, 1 mole of 2-aminoethyl sulfuric acid and 2 moles of sodium hydroxide in 10 per cent aqueous solution, the reaction being carried out according to the method of Example 1. The yield after purification by distillation in vacuo is 46 mole per cent. The 2-aminoethyl-n-propyl sulfide product is a colorless oil boiling at 84°-87°C. under 25 mm. pressure; the density at 25°C. is 0.9294 and the index of refraction, n_D^{20} , is 1.4832. On analysis the sulfur content is found to be 26.8.

As will be evident to those skilled in the art, various modifications of this invention can be made, or followed, in the light of the foregoing disclosure and discussion, without departing from the spirit or scope of the disclosure or from the scope of the claims.

I claim:

1. A process for the preparation of an alkyl amino sulfide having a composition in accordance with the following structural formula

wherein R is an alkyl radical having not more than 16 carbon atoms, wherein R' is selected from the group consisting of alkylene, cyclopentylene and cyclohexylene radicals, said alkylene

ene containing not more than 10 carbon atoms, wherein R'' and R''' are each selected from the group consisting of hydrogen, alkyl, aryl, and aralkyl radicals, and radicals which together with each other and said nitrogen form a heterocyclic ring, and the sum of the total number of carbon atoms in R'' and R''' is not greater than 10, said process comprising reacting one molecular equivalent of an aliphatic mercaptan having the structural formula R-S-H, wherein R is as above described, with one molecular equivalent of a substituted sulfuric acid having the structural formula

wherein R', R'', and R''' are as above described, in the presence of an alkaline-reacting agent selected from the group consisting of alkali metal oxides, alkali metal hydroxides and alkaline salts of an alkali metal, heating the resulting admixture for a period of from 10-15 hours at a temperature in the range of 100-110°C. and thereafter for a period of 20-30 hours at a temperature higher than 110°C. but not above 150°C. then adding to the resulting reaction mixture, maintained at a temperature below 15°C., from one to two moles of an alkali metal hydroxide, in aqueous solution in a concentration of at least 50 weight per cent, per mole of sulfide product therein, whereby alkyl amino sulfide product is obtained as a separate oil phase free from unreacted mercaptan and acid reactants, and recovering said oil phase as a purified product of the process.

2. The process of claim 1 wherein said mercaptan is tert-butyl mercaptan and wherein said sulfuric acid is 2-aminoethyl sulfuric acid.

3. The process of claim 1 wherein said mercaptan is tert-butyl mercaptan and wherein said sulfuric acid is 4-aminocyclohexyl sulfuric acid.

4. In a process for the production of an alkyl amino sulfide by reacting an aliphatic mercaptan with an amino sulfuric acid in the presence of an alkaline reacting agent, said alkyl amino sulfide being characterized by the structural formula

wherein R is an alkyl radical having not more than 16 carbon atoms, R' is selected from the group consisting of alkylene, cyclopentylene and cyclohexylene radicals, said alkylene containing not more than 10 carbon atoms and R'' and R''' are each selected from the group consisting of hydrogen, alkyl, aryl, and aralkyl radicals and radicals which together with each other and said nitrogen form a heterocyclic ring, the sum of the total number of carbon atoms in R'' and R''' being not greater than 10, said mercaptan being characterized by the structural formula R-S-H, wherein R is as above described and said amino sulfuric acid being characterized by the structural formula

wherein R', R'', and R''' are as above described, the improvement comprising maintaining the resulting reaction mixture at a temperature below 15°C. and adding thereto from 1 to 2 moles of alkali metal hydroxide in aqueous solution

in a concentration of at least 50 weight per cent, per mole of said sulfide product therein, whereby alkyl amino sulfide product is obtained as a separate oil phase free from unreacted mercaptan and acid reactants, and recovering said oil phase as a purified product of the process.

5. The improvement of claim 4 wherein said reaction mixture is maintained at ice temperature during the addition thereto of said aqueous alkali metal hydroxide.

6. The improvement of claim 5 wherein said alkali metal hydroxide is sodium hydroxide.

7. In a process for the production of 4-amino-cyclohexyl-tert-butyl sulfide by reacting tert-butyl mercaptan with 4-aminocyclohexyl sulfuric acid in the presence of an alkaline reacting agent at a temperature within the range of 50 to 150° C., the improvement comprising maintaining the resulting reaction mixture at a temperature below 15° C. and adding thereto from 1 to 2 moles of an alkali metal hydroxide in aqueous solution in a concentration of at least 50 weight per cent, per mole of 4-aminocyclohexyl-tert-butyl sulfide product therein, whereby 4-aminocyclohexyl-tert-butyl sulfide product is obtained as a separate oil phase free from unreacted mercaptan and acid reactants, and recovering said oil phase as a purified product of the process.

8. In a process for the production of 2-aminoethyl-tert-butyl sulfide by reacting tert-butyl mercaptan with 2-aminoethyl sulfuric acid in the presence of an alkaline reacting agent at a temperature within the range of 50 to 150° C., the improvement comprising maintaining the resulting reaction mixture at a temperature below 15° C. and adding thereto from 1 to 2 moles of an alkali metal hydroxide in aqueous solution in a concentration of at least 50 weight per cent, per mole of 2-aminoethyl-tert-butyl sulfide product therein, whereby 2-aminoethyl-tert-butyl sulfide product is obtained as a separate oil phase free from unreacted mercaptan and acid reactants, and recovering said oil phase as a purified product of the process.

9. In a process for the production of 2-aminoethyl-tert-octyl sulfide by reacting tert-octyl mercaptan with 2-aminoethyl sulfuric acid in the

presence of an alkaline reacting agent at a temperature within the range 50 to 150° C., the improvement comprising maintaining the resulting reaction mixture at a temperature below 15° C. and adding thereto from 1 to 2 moles of an alkali metal hydroxide in aqueous solution in a concentration of at least 50 weight per cent, per mole of 2-aminoethyl-tert-octyl sulfide product therein, whereby 2-aminoethyl-tert-octyl sulfide product is obtained as a separate oil phase free from unreacted mercaptan and acid reactants, and recovering said oil phase as a purified product of the process.

10. A process for the manufacture of 2-aminoethyl-tert-octyl sulfide comprising admixing tert-octyl mercaptan with 2-aminoethyl sulfuric acid in a mole ratio thereto within the limits of 1:1 to 1:3, heating the resulting admixture in the presence of aqueous sodium hydroxide for a period of from 10-15 hours at a temperature in the range of 100-110° C. and thereafter for a period of from 20-30 hours at a temperature higher than 110° C. and not above 150° C., adding to the resulting reaction mixture from one to two mols of an alkali metal hydroxide in aqueous solution per mol of 2-aminoethyl-tert-octyl sulfide therein, whereby a separate oil phase comprising said 2-aminoethyl-tert-octyl sulfide is formed and is free from unreacted mercaptan and acid, and recovering said separated oil phase as a product of the process.
